W. PATON.

DOOR HANDLE.

APPLICATION FILED AUG. 27, 1914.

1,164,958.

Patented Dec. 21, 1915.

UNITED STATES PATENT OFFICE.

WILLIAM PATON, OF LONGFORD MILLS, ONTARIO, CANADA.

DOOR-HANDLE.

1,164,958.

Specification of Letters Patent. Patented Dec. 21, 1915.

Application filed August 27, 1914. Serial No. 858,871.

To all whom it may concern:

Be it known that I, WILLIAM PATON, a subject of the King of Great Britain, and resident of the town of Longford Mills, county of Ontario, Province of Ontario, in the Dominion of Canada, have invented certain new and useful Improvements in Door-Handles, of which the following is a specification.

The invention relates to improvements in door handles as described in the present specification and shown in the accompanying drawings that form part of the same.

The invention consists essentially of the novel means employed for fastening the shanks of the knobs to the door in a mortised lock.

The objects of the invention are to devise a form of handle which will constantly retain the knobs in a fixed position longitudinally in relation to the door and thus prevent rattling and accidental displacement of the knobs, to construct a simple form of door handle that will lend itself readily to adjustment and generally to provide a cheap, efficient and durable door handle.

In the drawings, Figure 1 is a perspective view showing one door knob and shank partly broken away disclosing the adjusting mechanism also partly broken away and a portion of the spindle. Fig. 2 is a longitudinal sectional view of the invention showing it attached to a door. Fig. 3 is a cross sectional view on the line E—E in Fig. 2. Fig. 4 is a cross sectional view on the line A—A in Fig. 2. Fig. 5 is a cross sectional view on the line B—B in Fig. 2. Fig. 6 is a cross sectional view on the line C—C in Fig. 2. Fig. 7 is a cross sectional view on the line D—D in Fig. 2.

Like numerals of reference indicate corresponding parts in each figure.

Referring to the drawings, 1 is the door knob having the shank 2 and the threaded spindle hole 3 in said shank leading inwardly from the bed of a squared recess 4.

5 is a spindle having straight sides 6 intermediate of its length, that is to say of square cross section or otherwise for a portion of its length and at either end having the corners of the squared shape beveled and threaded as at 7 leaving the flat surfaces 8.

9 is a sleeve having the reduced squared portion 10 slidably mounted on the flat surfaces 8 of the spindle 6 and the larger portion 11 circular in shape. The reduced end

10 is slidably mounted on the flat surfaces 8 and fits into the correspondingly squared recess 4 so that said sleeve 9 turns with said shank 2 and consequently the spindle 5 turns with the turning of the knob 1.

12 is a thimble screw threaded onto the spindle 5 beyond the shank 2 and having the circular flange 13 at one end thereof.

14 is a helical spring encircling the periphery of the thimble 12. The thimble 12 is telescopically arranged in the sleeve 9, the end of said sleeve engaging the spring 14, the latter forming a cushion bearing for said sleeve.

15 is a knob having the shank 16, said shank having a threaded spindle hole 17 into which the other end of the spindle fits, being held therein by the sleeve 18 slidably mounted on the spindle and having the squared end 19 which fits into the recess 20 in the shank 16. The holes in the door 21 are made to suit this device being little different from the present practice.

22 are plate shields encircling the shanks of the knobs and secured to the door.

It will be seen that in installing these door handles, the spindle is first inserted in the knob 15. The other end of the spindle is then inserted through the door and through the mortise lock until a portion of the threads of the other end extends beyond the other side of the door. The thimble 12 along with the spring 14 is then secured onto the spindle to the proper position. Then the sleeve 9 is pushed up against the spring and followed up by the shank 2. When the said shank has reached the sleeve 9, said sleeve is grasped and drawn up over the thimble 12 thus compressing the spring 14, then while the sleeve 9 is in this position the shank 2 is screwed up until it again reaches the said sleeve. On releasing the grip from said sleeve the spring 14 forces the squared portion 10 back into the recess 4 of the shank 2 and thus prevents it from being removed until the spring is again compressed by drawing the sleeve up on to the thimble. When these parts have been adjusted the shield 22 which has previously been slipped over the shank 2 and up toward the knob, is brought back and securely fastened to the door in the usual way.

What I claim is:

In door handles, a pair of knobs having shanks provided with squared recesses in their ends and threaded holes extending in-

wardly from the beds of the squared recesses in the ends of said shanks, a spindle having longitudinal flat surfaces for sliding parts and threaded portions, a non-rotatable sleeve 5 sliding on said spindle having a squared outward projection extending into a squared recess in one knob, a non-rotatable sleeve having a squared outward projection extending into the corresponding recess in the other 10 knob sliding on said spindle and forming an annular recess between itself and said spindle, a thimble having a flange at its inner end

and screw threaded on to said spindle and registering with said annular recess and a spiral spring encircling said thimble and engaging the inner face of the last mentioned sleeve beyond said recess and locking the knob shanks to said spindle. 15

Signed at Orillia, Ontario, this fifteenth day of June 1914.

WILLIAM PATON.
